UNITED STATES PATENT OFFICE.

GALELMA BUTCHER, OF NORFOLK, VIRGINIA.

CASEMENT-WINDOW-ADJUSTMENT CONSTRUCTION.

Application filed February 24, 1926. Serial No. 90,364.

This invention relates to improvements in window constructions.

The primary object of this invention is the provision of a casement window adjustment construction, which will permit the removal or adjustment of the sash of the window construction.

A further object of this invention is the provision of an adjustable mounting for casement windows by means of which the sash may be readily opened to various degrees for ventilation, or be entirely removed with ease.

Other objects and advantages of this invention will be apparent during the course of the following detailed description.

In the accompanying drawing, forming a part of this specification, and wherein similar reference characters designate corresponding parts throughout the several views,

Figure 1 is an inside elevation of a casement window, showing the sash closed, with certain adjustment bolts for locking the sash to the frame when in closed position.

Figure 2 is a fragmentary vertical sectional view taken thru the casement window, showing the ventilating relation of the sash with respect to the window opening of the frame.

Figure 3 is a fragmentary sectional view taken thru details of the window construction, with the sash in closed locked relation with respect to the window frame.

Figure 4 is a sectional view taken substantially on the line 4—4 of Figure 1.

Figure 5 is a sectional view taken substantially on the line 5—5 of Figure 2.

Figure 6 is a perspective view of a sash supporting strip adapted for adjustable positioning on the window frame.

Figure 7 is a fragmentary perspective view showing the lower corner of the window frame, and its construction for receiving a sash and adjustable supporting parts.

In the drawing, wherein for the purpose of illustration is shown only a preferred embodiment of this invention, the letter A may generally designate the improved casement window adjustment construction, which may comprise a frame B within which the sash C is mounted for adjustment by means D.

As is normally understood, the frame B is provided with an opening, within which the single casement sash C is positioned to entirely fill the opening. It is a main objec-

tion of casement windows, that they cannot be readily opened, nor the sashes removed, nor the same opened to various adjustments for ventilating purposes.

The frame B is of course of any approved construction, and comprises the horizontal upper piece or yoke 10; sill 11; and side stiles or pieces 12, which define the opening 13 adapted to receive the sash C. The yoke 10 has the conventional stop strip or bead 15; and the side stiles or pieces 12 have vertical outer stop strips 16, to retain the sash C in position. The stool 18 is mounted in appropriate relation upon the sill 11, with its rear edge in spaced relation with the inside surface of the stop beads 16 of the side stiles providing side recesses 19 just above the sill 11, adapted to cooperate in detachably receiving reduced ends 20 of certain detachable adjusting strips 25 which comprise part of the means D, and are placed at each side of the opening 13 in movable relation with the side stiles 12.

The sash C is of the type adapted to conform to the opening 13, having no sliding space within the opening 13. This sash C comprises the side rails 30 and 31; top rail 32 and bottom rail 33 supporting the pane of glass 34 therein.

The means D includes the adjusting strips 25, which as above mentioned are adjustably and detachably related to the side stiles or frame pieces 12 of the frame B. As illustrated in Figure 6 and elsewhere in the drawing, these adjusting strips 25 are preferably of one piece construction, although they may be formed other than of one piece. Each is preferably grooved inwardly of its window opening side to provide a channel 35 extending longitudinally of the strip 25; to one side of the channel 35 providing a stop bead 36 which faces outwardly from the window sash, and at the opposite side providing a preferably beveled stop bead 37 which faces to the inside of the window sash, or faces inwardly of the room in which the casement window is provided. The body of the strip 25, along the channel 35 is provided with a vertical series of spaced openings 38 therein, adapted to receive the shank 39 of a spring bolt arrangement 40 which is carried by the sash rail or rails 30 or 31, and which will be subsequently described, and whereby to connect the sash to the strips 25.

The lower end of each strip 25 is, as above

mentioned, provided with the stepped end 20 adapted to be received in the recess 19 of the frame B; the end of the strip 25 being removed upwardly from the lower edge, along the stop bead 37, to provide the reduced portion 20, in order to provide a stay, so to speak, to maintain the strip 25 in place. Similarly, the upper end of the strip 25 is reduced, providing a shoulder 40, adapted to abut against the inside edge of the stop bead 15 of the yoke 10, in order to prevent the outward swinging of the shank supporting strip 25 with respect to the window opening 13.

15 Each of the strips 25 is preferably provided with a novel catch or retainer 42, including a leaf 43 hinged as at 44 on the inside surface of the stop bead or portion 37 of the strip 25; the hinged piece 43 including an arcuate projection or detent 46, adapted to enter an opening 47 provided transversely thru the strip 25, upon which the retainer is hinged; and also to enter a socket 48 formed in the frame B, inwardly 20 of the side member 12 thereof. Thus, with the catch 42 located on the strip 25 above the reduced portion 20, it is readily apparent that with the detent 46 locked in position, the strip 25 will be held in the casement 25 opening against liability of accidental detachment until the retainer 43 is swung inwardly towards the casement opening, parallel with the plane thereof, in order to remove the detent 46 from its sockets 47 and 30 48, as can readily be understood.

As an additional retainer to prevent lateral displacement of the strips 25, when the same are swung forwardly to position the sash in location to be opened, it is preferred 40 to provide substantially L-shaped brackets 50 on the stool portion 18 of the sill 11, which include upstanding flanges 51 adapted to abut against the lower portions of the stop beads 37 of the strips 25, as illustrated 45 in Figures 1 and 4 of the drawing, in order to limit any inward movement of the strips 25, towards the window opening, and thus prevent lateral displacement thereof.

The sash C has the rails 30 and 31 thereof 50 slidably positioned in the channels 35 of the adjusting strips 25, so that it can be readily understood, upon forward tipping of the upper ends of the strips 25, into the room, to annularly position them at an acute 55 angle with respect to the window opening, the sash C may be readily moved upwardly to various degrees, for ventilating purposes. To this end, it is preferred to provide some means to retain or hold the lower ends of 60 the strips 25, against falling movement into the room, and to hold the strips 25 at the desired angular relation. To this end, it is preferred to provide a novel friction catch 55, on each of the strips 25, which includes 65 a plunger 56, mounted within a cylindrical

casing 57, and urged by a spring 58, so that the head extension 59 thereof is normally forced toward the adjacent frame stile 12, for the purpose of entering a socket 60 of a wear plate 61 mounted on the frame side 70 stile; the said plunger only so entering the socket 60 when the strips 25 are tipped forwardly at their upper ends, so that it can readily be understood with the reduced portions 20 held in position in the recess 19; the section catches 55 will limit the inward swinging of the strips 25, and prevent their overbalancing.

The strips 25 are so positioned that the sash C may be swung upwardly just sufficiently to miss the inside edge of the window frame B, at the yoke 10 thereof, as is illustrated in Figure 2 of the drawing.

In order to hold the sash C in the desired vertical adjustment with respect to the window opening and the strips 25, the spring bolts 40 are provided, as above mentioned; the same being slidably mounted in a horizontal relation in the lower portions 30 and 31 of the sash C. Each of these spring bolts 40 includes a hollow cylindrical casing 65, embedded in the rail 30 or 31 of the same, as the case may be; the plunger portion, of which the shank 39 is a part, being slidably mounted axial thru this casing 65, and urged by means of a spring 67 in the casing portion 65, so that the shank 39 of this plunger is normally forced laterally toward the side stile of the window casing. In fact, the shanks 39 are of sufficient length to extend 100 entirely thru the openings 38 of the strips 25, and enter special sockets 70 provided therefor in the stiles 12, in order to lock the sash C, as well as the strips 25 in closed position in the window opening 13, against liability of detachment. The shanks 39 of the spring bolts do not enter the sockets 70 when the window sash is tipped inwardly of the room, for ventilating adjustment.

As is illustrated in Figure 2, the sash C 110 may be slid upwardly and the spring bolts 40 at each side of the sash rails engaged in the desired openings 38 of the strips 25, in order to hold the sash C in a desired elevated and ventilated relation.

From the foregoing description of this invention it is apparent that a practical and simple type of casement window adjustment construction has been provided, by means of which small sashes for casement windows 120 may be economically mounted for detachment and ventilating adjustment. From a closed position it is merely necessary to release the detent 42. The operator next grasps the handle portions 80 of the plungers 125 of the spring bolts 40, and draws the same inwardly to remove the shanks thereof from the sockets 70 of the frame B. The strips 25, together with the sash C may then be swung bodily inwardly of the room, by 130

pivoting the same at its lower ends, until the strips at their lower corners abutting against the inside surface of the stop beads 16 of the frame B, and in this position the 5 friction catches 55 will engage at their plungers in the sockets 60, as illustrated in Figure 5 of the drawing, to hold the strips 25 in place against liability of forward tipping. The lateral displacement of the friction 10 catches from their sockets 60 is prevented by reason of the flanges 51 of the brackets 50 above mentioned, and the sash C may be slid upwardly to any adjustment in the manner above described.

15 Various changes in the shape, size, and arrangement of parts may be made to the form of invention herein shown and described, without departing from the spirit of the invention or the scope of the claims.

20 I claim:

1. In a casement window adjustment construction the combination with a frame having an opening therein, a single sash for said opening adapted to normally entirely fill the 25 same, side strips movably supported by the frame at the sides of the window opening, said side strips having channels therein adapted to receive the sides of the sash in a 30 slidable relation, means to lock the side strips 35 within the window opening with the sash closing the window opening, and means to adjustably position the strips in a tipped relation with respect to the window opening to permit sliding of the sash outwardly of said frame opening.

2. In a casement window adjustment construction the combination with a frame having an opening therein, a single sash for said opening adapted to normally entirely 40 fill the same, side strips movably supported by the frame at the sides of the window opening, said side strips having channels therein adapted to receive the sides of the sash in a slidable relation, means to lock the 45 side strips within the window opening with the sash closing the window opening, means to adjustably position the strips in a tipped relation with respect to the window opening to permit sliding of the sash outwardly of 50 said frame opening, and means to adjustably position the sash to desired positions along said strips for supporting the same at a desired elevation to open the window sash to a desired degree for variable ventilation.

55 3. In a casement window adjustment construction the combination of a casement frame having an opening therein, said frame including side members, a sill, and a top member, a sash adapted to normally entirely 60 fill said opening to close the same, side strips having stop bead means thereon to support the sash for sliding relation with respect to said side strips, means for releasably connecting the lower ends of said side strips to the side members of the frame to permit the

upper ends of said side strips to be tipped outwardly from the opening defined by the frame to a limited extent, whereby the window sash may be elevated outwardly of the opening of the frame by sliding upwardly 70 along said strips.

4. In a casement window adjustment construction the combination of a casement frame having an opening therein, said frame including side members, a sill, and a top 75 member, a sash adapted to normally entirely fill said opening to close the same, side strips having stop bead means thereon to support the sash for sliding relation with respect to said side strips, means for releasably connecting the lower ends of said side strips to the side members of the frame to permit the upper ends of said side strips to be tipped outwardly from the opening defined by the frame to a limited extent, whereby the window sash may be elevated outwardly of the opening of the frame by sliding upwardly 80 along said strips, and means upwardly carried by said strips for locking the strips in a detachable relation in said frame opening to position the sash in the opening against movement.

5. In a casement window adjustment construction the combination of a casement frame having an opening therein, said frame including side members, a sill, and a top member, a sash adapted to normally entirely 95 fill said opening to close the same, side strips having stop bead means thereon to support the sash for sliding relation with respect to said side strips, means for releasably connecting the lower ends of said side strips to the side members of the frame to permit the upper ends of said side strips to be tipped outwardly from the opening defined by the frame to a limited extent, whereby the window sash may be elevated outwardly of the opening of the frame by sliding upwardly 100 along said strips, means upwardly carried by said strips for locking the strips in a detachable relation in said frame opening to position the sash in the opening against movement, and means carried by said sash adapted to engage the sash strips when tipped outwardly of the opening of said frame for holding the sash in an adjusted elevated relation with respect to said side strips to open the sash to a desired degree 110 with respect to said frame.

6. In a casement window construction the combination with a casement frame having an opening therein, a single sash for the frame opening adapted to normally entirely fill the same, movable strips at the sides of the frame for slidably supporting the sash, and means supporting the strips at the sides of the frame, so that the lower ends of the strips may be pivoted in said frame, and the upper ends thereof swung outwardly of the opening of the frame so that the sash may 120 125 130

be swung upwardly along said strips out of the opening of the frame.

7. In a casement window construction the combination of a frame having an opening therein, a single sash adapted to normally entirely fill the opening, a pair of sash supporting strips, and means pivotally mounting said strips at the lower ends thereof in the opening of the window frame so that the upper ends thereof may be swung outwardly of the opening of the frame to a limited extent to incline the sash at an angle with respect to the window opening and permit the upward movement of the same out of the opening of the frame.

8. In a casement window construction the combination of a frame having an opening therein, a single sash adapted to normally entirely fill the opening, a pair of sash supporting strips, means pivotally mounting said strips at the lower ends thereof in the opening of the window frame so that the upper ends thereof may be swung outwardly of the opening of the frame to a limited extent to incline the sash at an angle with respect to the window opening and permit the upward movement of the same out of the opening of the frame, and means to vertically lock said strips in the frame opening with the sash closed in said frame opening.

9. In a casement window construction the combination of a frame having an opening therein, a single sash adapted to normally entirely fill the opening, a pair of sash sup-

porting strips, means pivotally mounting said strips at the lower ends thereof in the opening of the window frame so that the upper ends thereof may be swung outwardly of the opening of the frame to a limited extent to incline the sash at an angle with respect to the window opening and permit the upward movement of the same out of the opening of the frame, means to vertically lock said strips in the frame opening with the sash closed in said frame opening, and means to adjustably lock the sash at a desired elevation upon said strips when the latter are tipped in angular relation with respect to the frame opening as above mentioned.

10. In a casement window adjustment construction the combination of a frame having an opening therein, a single sash normally adapted to entirely close said opening, channeled side strips receiving the sash at the sides thereof in said channels, means to detachably lock the side strips in the frame opening to hold the sash therein to close the frame opening, and friction catch means at the lower ends of said channeled strips for engaging the frame when the upper ends of said strips are tipped outwardly of the frame opening to support the said strips in an inclined relation with respect to the window opening to permit the sash to be moved upwardly in an extended relation with respect to the frame opening.

GALELMA BUTCHER.
